N. J. ZUZULIN

AGITATOR OR SHAKER FOR STOVES OR FURNACES

Filed May 7, 1923

By *George A. Mathews*

Attorney

UNITED STATES PATENT OFFICE.

NICHOLAS J. ZUZULIN, OF MINOT, NORTH DAKOTA.

AGITATOR OR SHAKER FOR STOVES OR FURNACES.

Application filed May 7, 1923. Serial No. 637,318.

To all whom it may concern:

Be it known that I, NICHOLAS J. ZUZULIN, a citizen of the United States, residing at Minot, in the county of Ward and State of

5 North Dakota, have invented certain new and useful Improvements in Agitators or Shakers for Stoves or Furnaces, of which the following is a specification.

10 My invention relates to agitators or shakers for stoves, furnaces, or the like.

An important object of the invention is the provision of a device of this character, which will be capable of use with soft coal or lignite burners in such a manner that the 15 clinkers and coal are all consumed.

Another object of the invention is to provide a device of this character, which will be in the nature of an attachment and which may be readily attached to any furnace now 20 in use.

A further object of the invention is to provide a device of the above mentioned character, which will be characterized by extreme simplicity, and is strong and durable.

25 Other objects and advantages of the invention will be apparent during the course of the following description.

In the accompanying drawings forming a part of this specification, and in which like 30 numerals are employed to designate like parts throughout the same,

Figure 1 is a perspective view of a furnace provided with my invention,

Figure 2 is a side elevation of the same, 35 parts being in section,

Figure 3 is a transverse section taken through the shaker, showing the different portions of the shaker arms in dotted lines,

Figure 4 is a central longitudinal section 40 through the device, and,

Figure 5 is a perspective view of a modified form of the device.

In the drawings, wherein for the purpose of illustration is shown a preferred embodiment of my invention, the numeral 10 designates a furnace having a grate 11 of the usual construction. The furnace casing is provided with a threaded opening 12 in its front portion, said opening being arranged a substan-

50 tial distance above the grate 11 and adapted to receive the exteriorly threaded end of a tubular sleeve 13 having a radial flange 13' at its opposite end. Suitable clamping rings 14 are screwed onto the sleeve 13 and are arranged one on either side of the furnace casing. These clamping rings are provided

with extensions 15 and a bolt 16 serves to clamp the clamping rings to the wall of the furnace. This construction affords a very rigid mounting for the sleeve 13. 60

A shaft 17 fits loosely within the sleeve, and has a squared end 18 for the reception of a shaker crank 19, whereby the shaft may be rotated within the sleeve. This extends inwardly to about the center of the furnace and 65 the shaft extends therebeyond, and is provided with an enlarged head 20 which is eccentrically mounted on the shaft and which has its end screw threaded.

70 Radially extending arms 21 extend one to each side of the head 20. Each of these arms comprises a substantially flat body portion 22 which has an opening near its ends which receives the eccentrically mounted head 20. This body portion has both edges curved so 75 as to converge outwardly, and merge into an upstanding prong 23. Similar prongs 24 are carried by the body portion and are arranged to either side of the central prong so as to form a fork shaped agitating element. A 80 nut 25 is screwed onto the head 20 and serves to retain the arms thereon.

A supporting plate 26 is carried by the sleeve 13 and is arranged beneath the head 20 and arms 21. This plate is adapted to support 85 the arms in a substantially horizontal position as without this support these arms would swing downwards into a vertical position.

90 In operation, when the shaft 17 is turned by the crank 19, the arms 21 will partake of a combined rocking and reciprocating motion. This is due to the turning of the eccentrically mounted head 20 which as it revolves will act as a crank and reciprocate 95 the arms. The inner ends of these arms will also have a vertical movement due to the crank like movement of the head 20 and this vertical movement will be translated into a rocking motion due to the curved lower edge 100 contacting with the supporting plate. This is shown in Figure 3 by the dotted lines. The arms are prevented from sliding off of the head by the flange 13' on one side and by the nut 25 on the other side. 105

110 In the modification shown in Figure 5 the supporting plate is dispensed with and the sleeve 13 is provided with a radial extension 27 having its end bifurcated, forming a slot 28. The arm 29, nearest the sleeve carries a lateral extension 30 near its outer end which has a rounded shank with an en-

larged head at its end. This shank is adapted to slide in the slot 28. A lateral lug or pin 31 is carried by the opposite end of the arm 29 and is arranged on the side 5 farthest from the sleeve 13. This pin 31 enters an opening in the arm 32 and serves to support the same. When the shaft is rotated the arms will partake of the same combined reciprocating and rocking motion 10 as in the other form of the invention. The extension 30 will reciprocate in the slot 28 and will also serve as a pivot when the inner end of the arm moves vertically thereby resulting in a rocking motion. Due to 15 the pin 31 the other arm will partake of the same movement. The crank 19 need not be rotated but need only be oscillated as is usual in a grate.

The agitation caused by the forked agitating members will cause the fine ashes to descend and cause the fire to come down to and around the mechanism so as to hold the unburned clinkers in suspension and thereby cause a more complete combustion 25 which will result in the more economical use of soft coal and lignite.

It is to be understood that the form of my invention herewith shown and described is to be taken as a preferred example of the 30 same, and that various changes in the shape, form, size and arrangement of parts may be resorted to without departing from the spirit of my invention or the scope of the subjoined claims.

Having thus described my invention, what I claim is:

1. In an agitating device for a furnace, a shaft adapted to be rotatably mounted in the furnace, a head eccentrically mounted on the end of said shaft, and an agitating member mounted on said head whereby when the shaft is turned the agitating member will partake of a combined reciprocating and rocking movement.

2. In an agitating device for a furnace, a shaft adapted to be rotatably mounted in the furnace, an agitating member mounted on the shaft, and means whereby when the shaft is turned the agitating member will partake of a combined reciprocating and rocking movement.

3. In an agitating device for a furnace a sleeve adapted to be rigidly mounted in the furnace, a shaft adapted to be rotatably mounted in the sleeve and projecting therebeyond, a head eccentrically mounted on the shaft, agitating members rotatably mounted on the head, said agitating members comprising body portions having openings to receive the eccentrically mounted head, and prongs carried by said body portions, and means whereby said body portions are sup-

ported in a substantially horizontal position.

4. In an agitating device for a furnace a sleeve adapted to be mounted in said furnace and projecting through the outer wall thereof, said sleeve being adapted to be arranged above the grate of the furnace, a shaft rotatably mounted in said sleeve, means to turn the shaft, an eccentrically mounted head carried by the shaft, substantially flat arms mounted on the head, agitating prongs carried by said arms at their outer ends, means to retain the arms on the eccentrically mounted head, and means to retain the arms in a substantially horizontal position whereby when the shaft is turned, the arms will partake of a combined reciprocating and rocking movement.

5. In an agitating device for a furnace, the combination with a furnace having a grate, a sleeve adapted to be mounted in said furnace above the grate of the furnace, and adapted to project through the furnace casing, means to clamp the sleeve in rigid relation to the furnace, a shaft rotatably mounted within the sleeve and projecting therebeyond at both ends, means at the outer end to turn the shaft, a head eccentrically mounted on the inner end of the shaft, radially extending arms mounted on the head, agitating prongs carried by the radial arms at their outer ends, means to retain the arms on the head, and a supporting plate carried by the sleeve and arranged beneath the arms whereby when the shaft is turned the arms will partake of a combined reciprocating and rocking motion, in a substantially horizontal plane.

6. In an agitating device for a furnace, a sleeve adapted to be rigidly mounted in the furnace above the grate of the furnace and adapted to project through the furnace casing, a shaft rotatably mounted in the sleeve and projecting therebeyond at both ends, means on the outside end to turn the shaft, a cam carried by the inner end of the shaft, a pair of agitating members mounted on the cam, each agitating member comprising a substantially flat body portion having an opening to receive the cam and whose edges are curved so as to converge outwardly, and upstanding prongs carried by the outer ends of the body portion, and a supporting plate carried by the sleeve and arranged beneath the arms whereby when the shaft is turned the cam will coat with the curved edges of the body portions and the supporting plate in a manner to cause the arms to partake of a combined reciprocating and rocking motion.

In testimony whereof I affix my signature.

NICHOLAS J. ZUZULIN.
